METHOD AND APPARATUS FOR DRESSING
GRINDING WHEELSErnest Wildhaber, Brighton, N. Y., assignor to
Gleason Works, Rochester, N. Y., a corporation
of New York

Application December 29, 1945, Serial No. 638,029

19 Claims. (Cl. 125—11)

1

The present invention relates to methods and apparatus for dressing grinding wheels and particularly to methods and apparatus for dressing wheels, such as are used in grinding tooth surfaces of gears, face clutch members, and the like.

In the production of face clutch members, it is customary to chamfer or round off the tops of the teeth to facilitate engagement of the mating clutch members or to prevent interference of the top of a tooth of one member with the lower, flank portion of the tooth of the mating member. To produce the chamfer or round in a grinding operation, it is preferable to have a shoulder on the side of the grinding wheel which matches the straight or curved chamfer to be produced on the clutch teeth so that the sides of the teeth and the chamfered or rounded portions thereof may be ground simultaneously. Difficulty has been experienced, heretofore, however, in dressing the desired shape of shoulder on a wheel especially where the shoulder has had a substantial inclination to the side surface of the wheel, say more than 6°. The result has been that frequently it has been necessary to grind the sides of the teeth of a face clutch member in one operation and the chamfer or rounds in a separate operation.

Heretofore, moreover, whether shoulders have had to be dressed on the wheels or not, separate side and end dressing tools have been employed in dressing wheels which are intended to grind gears and face clutch members. Usually two tools at least, viz., a side dresser and an end dresser, have had to be employed for dressing a wheel for grinding clutch members and ordinarily, at least three tools, viz., two side dressers and an end dresser, have had to be employed for dressing a wheel for grinding gear teeth. Aside from their complication, therefore, the dressing mechanisms used heretofore have had the disadvantage that they do not dress a single continuous profile around the sides and tip of the wheel. The path of the end dresser intersects the path or paths of the side dressers at a slight angle, and there are slight angles, therefore, where the side and end dressers, respectively, leave off. Moreover, the unequal wear of the several diamonds causes imperfect blending of the dresser paths, and continuous resetting of the dresser tools is necessary.

One object of the present invention is to provide a dressing mechanism with which a grinding wheel profile, composed of both straight and arcuate portions, may be dressed in one con-

2

tinuous operation without any break in the profile outline.

Another object of the invention is to simplify the dressing operation and the dressing mechanism by enabling a single dressing tool to effect the dressing of the side and tip surfaces of a grinding wheel in a single continuous operation.

A further object of the invention is to provide a wheel dressing mechanism with which widely varying shapes may be dressed on the side and tip surfaces of a grinding wheel but nevertheless with a single dressing tool in a continuous dressing operation.

A further object of the invention is to provide 15 a dressing mechanism using a single tool, such as a diamond, to dress the sides and tip of the wheel and in which the tool will be maintained at the correct angle to each surface being dressed throughout all of its movements across the sides and tip of the wheel.

A further object of the invention is to provide 20 a dressing mechanism with which a shoulder, even of substantial inclination and even of curved shape, may be dressed on the side of a grinding wheel, so that the wheel may be used to grind a round or chamfer on the teeth of a clutch member simultaneously with the grinding of the sides of its teeth.

Another object of the invention is to provide 25 an efficient dressing process in which a composite profile, including convex and concave profile portions or including side and tip portions, may be dressed on a grinding wheel while perfect blending is obtained between the various portions of the wheel profile.

A further object of the invention is to provide 30 a dressing mechanism with which each surface of a grinding wheel may be dressed readily in such manner as not to "burn" the work in the grinding operation. It has been discovered, for instance, that the tip surface of an annular grinding wheel will most likely "burn" the work unless the spiral path dressed on the tip surface is of substantially the same pitch as the spiral path dressed on the inside of the wheel. It has been found, too, that ordinarily the outside surface of an annular grinding wheel should be dressed to a coarser pitch than the inside surface of the wheel to avoid "burning." This means that the tip surface of the wheel should be dressed at a substantially constant speed equal to the speed at which the diamond is moved across the inside of the wheel in the dressing of the same, and less than the speed of movement of the diamond in dressing the outside of

the wheel. The uniformity of dressing of the tip and inside surfaces of the wheel can be obtained to a far greater degree and with much greater ease with the dressing mechanism of the present invention than with dressing mechanisms in which separate dressing tools are employed for dressing the sides and tip of the wheel, yet without interfering with the attainment of the desired coarseness on the outside of the wheel.

Still another object of the invention is to reduce the length of the path of movement of the dressing tool required to dress the side surface of a grinding wheel and thereby increase the life of the dressing tool employed.

Other objects of the invention will be apparent hereinafter from the specification and from the recital of the appended claims.

In the drawings:

Fig. 1 is a fragmentary axial sectional view of an annular grinding wheel for grinding one member of a face clutch pair and illustrating somewhat diagrammatically certain principles followed in dressing such a wheel according to the present invention;

Fig. 2 is a fragmentary axial sectional view of an annular wheel such as may be employed in grinding the other member of the clutch pair;

Figs. 3 and 4 are fragmentary views illustrating modified forms of face-clutch grinding wheels, and certain principles of dressing such wheels with the method and apparatus of the present invention;

Figs. 5 and 6 are fragmentary sectional views showing two types of gear grinding wheels that may be dressed according to the present invention;

Fig. 7 is a sectional view taken in a plane normal to the outside surface of a rotary annular grinding wheel showing the dressing tool in engagement with the outside surface of the wheel, and illustrating diagrammatically the motions preferably employed with the present invention in dressing this wheel;

Fig. 8 is a corresponding view showing the dressing tool in engagement with the inside surface of a wheel and illustrating diagrammatically the motions that may be employed in dressing this surface;

Figs. 9 and 10 are views similar to Figs. 7 and 8, respectively, illustrating modified methods of dressing the outside and inside surfaces, respectively, of annular grinding wheels;

Fig. 11 is a fragmentary side view of the wheel of Fig. 1, showing the projected path of movement of its diamond across the outside surface of this wheel;

Fig. 12 is a sectional view of a dressing mechanism constructed according to one embodiment of the present invention and adapted particularly for the dressing of grinding wheels of the types shown in Figs. 1 to 4 inclusive;

Fig. 13 is a sectional view taken on the line 13—13 of Fig. 12, looking in the direction of the arrows;

Fig. 14 is a sectional view taken on the line 14—14 of Fig. 13, looking in the direction of the arrows;

Fig. 15 is a fragmentary view showing details of the gearing for operating the dressing mechanism;

Fig. 16 is a developed view of the track of the control cam employed in the mechanism of Fig. 12;

Fig. 17 is a view similar to Fig. 12 but showing

a modified form of control cam such as may be used when dressing a gear grinding wheel of the general type shown in Figs. 5 and 6;

Fig. 18 is an elevational view of a still further form of cam that may be employed in the dressing mechanism when dressing a grinding wheel of either of these types;

Figs. 19, 20 and 21 inclusive are diagrammatic views illustrating successive positions of the dressing tool in dressing a gear grinding wheel according to one embodiment of this invention;

Fig. 22 is a transverse sectional view through the housing showing the rotary piston that actuates the dressing mechanism.

In the embodiments of the invention illustrated, dressing of the desired profile shape on a grinding wheel is effected during rotation of the wheel by movement of the dressing tool about and along an axis and by swinging the tool about a second axis angularly disposed to the first axis and preferably intersecting the first axis. The motion in the direction of the first axis is independent of the motion about that axis and may take place while the motion about that axis is stopped. In dressing a side surface of the wheel, the dressing tool is usually swung about the first axis while being moved in the direction of that axis. In dressing the tip surface of the wheel or a shoulder on the side of the wheel, the turning motion about the first axis may be stopped and the tip or shoulder may be dressed solely by axial motion of the tool in the direction of the first axis. The swinging motion about the second axis serves to maintain the diamond or other dressing tool at the correct angle to the surface being dressed during the dressing operation. It serves to position the diamond correctly for dressing the top of the wheel or a shoulder of the wheel. It operates to maintain the dressing tool at a proper angle to the wheel so that uniformly smooth surfaces may be dressed on the sides and tip of the wheel.

In dressing a grinding wheel that has a shoulder, for instance, the dressing tool may be moved in the direction of the first axis while the tool is positioned by movement about the second axis so that it makes a constant angle with the surface of the shoulder as it travels across that surface. Then the side of the wheel adjacent the shoulder is dressed by swinging the tool about the second axis to position it at the correct angle with reference to the side surface, and the tool is swung about the first axis while being moved in the direction of that axis. A round at the juncture of the side and tip of the wheel may then be dressed by swinging the tool about the second axis to maintain the tool at the correct angle, while continuing the movements of the tool about and in the direction of the first axis.

The tip of the wheel may be dressed by moving the tool in the direction of the first axis after it has been swung around the corner by the described movement about the second axis. If the opposite side of the wheel is also to be dressed, as is usually the case with a wheel for grinding gears, the tool is again swung about the second axis to position it correctly, and the round at the juncture of the tip and the said opposite side of the wheel is dressed by reversing the direction of swing of the tool about the first axis and simultaneously feeding the tool further on in the direction of the first axis. The opposite side of the wheel is then dressed by continuing the swing of the tool in the reversed direction about the first axis while feeding the tool further on in the

first axis while feeding the tool further on in the

direction of that axis. The swinging movement about the first axis is, therefore, reversed for dressing opposite sides of the wheel, but in the embodiment illustrated the axial feed movement is continuous in the same direction during dressing of both sides and of the tip of the wheel.

In Fig. 1, 25 denotes a rotary annular grinding wheel such as may be employed in the grinding of one member of a face clutch pair which has longitudinally curved teeth. In the grinding of such clutch members, opposite sides of spaced teeth of each clutch member are ground simultaneously. One member of the clutch pair may have its opposite side tooth surfaces ground with the outside surface of a grinding wheel while the other member of the clutch pair may have its opposite side tooth surfaces ground with the inside surface of a grinding wheel. The wheel 25, shown in Fig. 1, is adapted to grind with its outside surface 26 while the wheel 45 of Fig. 2 is adapted to grind with its inside surface 46.

The wheel 25 is intended to grind a round along the tops of the teeth of the clutch member simultaneously with the grinding of the sides of the teeth, the bottoms of the tooth spaces, and the fillet curves which join the sides with the bottoms. For these purposes the wheel is provided with a shoulder 28, an outside surface 26, a tip surface 27, and with rounds 41 and 42, joining the shoulder 28 with the side 26 and the side 26 with the tip surface 27, respectively. The wheel axis is denoted at 40.

For dressing the wheel 25, a diamond 30 may be used. This diamond is swingable about an axis 31 (Figs. 1 and 7), as indicated by arrow 32, and is movable in the direction of the axis 31, as indicated by arrow 33. It may also be tipped about an axis 35, as indicated by arrow 36, which is here shown as passing through the point of the diamond and tangent to the wheel surface. The dressing mechanism is preferably so positioned that the axis 31, about which the dressing tool rotates and is moved axially, projects into a position parallel to the tip surface 27 of the wheel and inclined to the normal 38 to the outside surface 26 of the wheel at mean point 39.

The shoulder 28 of the wheel is dressed by first swinging the diamond about axis 35 to incline the dressing tool 30 to the correct angle to surface 28 and by then moving the dressing tool in the direction of the axis 31. The round 41 at the juncture of shoulder 28 and side 26 may be formed by swinging the diamond about axis 35 to correctly position the diamond, and then moving the diamond about and in the direction of axis 31. In the movement about axis 35, axis 31 is returned to the position shown in Figs. 1 and 7. For dressing the side of the wheel, the diamond continues to be swung about axis 31 while being moved in the direction of that axis. The timing of these two movements depends on the shape to be dressed. The path traced by the point of the diamond during dressing of the side surface is shown in projection at 43 in Fig. 11. The round 42 at the juncture of the side surface 26 and the tip surface 27 is formed by swinging the diamond about axis 35 while continuing to move the diamond about and in the direction of axis 31. The tip surface 27 may be formed solely by axial motion of the diamond in the direction of the axis 31 after it has been swung around the corner 42. There is no turning motion required about the axis 31, the swinging motion about the axis 35 serving to position the diamond at the correct angle to the tip surface 27.

The various described motions of the diamond take place in a single continuous operation and as the diamond passes over the different surfaces of the wheel, the wheel is, of course, rotated continuously on its axis 40. The diamond is preferably moved at a uniform velocity about and in the direction of axis 31 during the various dressing steps.

The grinding wheel 45 has an inside surface 46, a tip surface 47, an inside shoulder 48, and rounds 61 and 62, joining the shoulder with the side and the tip surface with the side surface, respectively. For dressing the wheel 45, diamond 50 may be moved about and in the direction of axis 51, as denoted by the arrows 52 and 53 (Fig. 8), and is tilted about axis 55, as denoted by the arrow 56. The dressing mechanism is preferably positioned as before with axis 51 parallel to the tip surface of the wheel and inclined to a normal at a mean point to the inside surface of the wheel. The shoulder 48 of the wheel may then be dressed by moving the diamond in the direction of axis 51 after it has been positioned at the correct angle to the surface 48 through rotation about axis 55. The round 61 is dressed by swinging the diamond about axis 55 while moving it about and in the direction of axis 51. The side 46 is dressed by rotating the diamond about axis 51 while moving it in the direction of that axis. The round 62 is dressed by again swinging the diamond about axis 55 while moving it about and in the direction of axis 51. Finally the tip surface 47 of the wheel is dressed by moving the diamond in the direction of axis 51. The wheel 45, of course, rotates on its axis 60, at a uniform velocity throughout the whole of the dressing operation, and, as before, the motions of the dressing tool are preferably all at uniform rates.

Wheels like wheels 25 and 45 are used for grinding face clutch members whose side surfaces are of positive pressure angle. For grinding a face clutch member, whose side surfaces are of zero pressure angle, a wheel such as shown at 65 in Fig. 3 may be employed. This wheel has an outside surface 66 of positive pressure angle and a tip surface 67 which is substantially perpendicular to the outside surface 66. Rounds 72 and 73, respectively, join the side with the tip surface and the side with the shoulder 68, respectively.

For dressing the wheel 65, the dressing mechanism is again preferably positioned so that the axis, about which the diamond rotates and moves axially, is parallel to the tip surface of the wheel. This axis is designated 71. In this case, the axis 71 is normal to the outside surface 66 of the wheel and passes through the mean point 69 of that surface. In the wheel shown, the radii of the convex round 72 and of the concave portion 73 are equal. The various portions of the profile of wheel 65 may be dressed in a manner similar to the methods of dressing wheels 25 and 45, previously described, as will be obvious from the preceding description.

If it is desired to dress a wheel which has a convex round 72' (Fig. 4) at the juncture of side 66' and tip 67' which is of slightly different radius of curvature from the concave portion 73' which joins the shoulder 68' and the side 66' of the wheel, this may be accomplished by slightly advancing the diamond from the position which it occupies when dressing the wheel 65 of Fig. 3.

The dotted lines in Fig. 3 show the kind of wheel profile that would be produced if the width 75 of the grinding profile were increased appreciably

as compared with its depth, while still using the same motions of the dressing tool. The tip surface 67 of the wheel would then become slightly convex, and the shoulder 68 would then be slightly concave.

The axis, about which the diamond is tilted, may be inclined at any suitable angle to the axis about and along which the diamond moves. These two axes need not be at right angles. Thus, as shown in Fig. 9, for dressing a grinding wheel 10 which is to grind with its outside surface 26, the diamond 30 may again be positioned to move about and along an axis 31, as denoted by the arrows 32 and 33, but it may be tipped about an axis 35', as indicated by arrow 36', which passes through the point of the diamond but is disposed at an acute angle to the axis 31 and is inclined to the wheel periphery. Likewise, for dressing a grinding wheel 45, which is to grind with its inside surface 46, the diamond 50 may be tipped about an axis 55', as indicated by arrow 56', which is inclined at an obtuse angle to axis 51 and is inclined to the wheel surface 46.

The position of the axis, about and along which the diamond moves, may also be varied. Thus, as indicated in Fig. 10, this axis might be at 75° perpendicular to axis 55' instead of at 51. In this case, a slightly different profile would be produced on the wheel if the same motions were employed as before.

One way in which the dressing mechanism may be constructed to practice the present invention is illustrated in Figs. 12 to 16 inclusive. Here the diamond pin or rod 80 is secured, by means of a clamping screw 83, in a split clamp formed at one end of an arm 82. The arm 82 has an elongated shank portion 84, that is secured by a nut 85 in the sleeve portion 86 of a shank-type bevel pinion 87. This bevel pinion is journaled by means of the sleeve portion 86 on anti-friction bearings 88 and 89 in one arm of a generally L-shaped holder 90. The other arm 91 of this holder is cylindrical and is mounted to rotate and reciprocate in an elongated sleeve-type anti-friction bearing 92. The balls 93 of this bearing roll on the outside cylindrical surface of arm 91 and on the inside cylindrical surface of the supporting frame or housing 95 of the dresser mechanism.

The arm 91 of the holder 90 has a projection 97 (Fig. 13) at one side which is of general V-shape in cross-section (Fig. 14) and which constitutes a follower that engages in the groove or trackway 98 of a cam 100. There is a bar or strap 101 secured in a slot in arm 91 by screws 102. This bar or strap extends parallel to projection 97 and acts as a follower which engages the periphery of the cam 100 at a point diametrically opposite the point of engagement of the follower 97 with the cam groove 98.

The groove or trackway 98 has a constant depth, that is, its bottom follows the outside contour or periphery of the cam 100. The groove serves to control the axial motion and axial position of the holder 90. The outside contour or trackway of the cam 100 controls the rocking motion of the holder 90. This rocking motion obviously is controlled only by the shape of the periphery of cam 100 and is independent of the shape of the groove 98. It would be the same if no groove 98 at all were provided in the cam 100.

The cam 100 is keyed or otherwise secured to a shaft 103. This shaft has an arm or paddle 104 secured to it which constitutes a rotary piston. This piston is adapted to operate in a cylinder

5 formed in the frame or housing 95 and between fixed stops (not shown) that are provided in the cylinder. By application of fluid pressure to one side or the other of the piston 104 through ducts 112 and 112' (Fig. 22), then, the shaft 103 and cam 100 may be oscillated to impart rotary and axial movement to the holder 90, as determined by the shape of cam track 98 and the peripheral surface of the cam.

Connected to the shaft 103, as by means of a conventional face clutch 105, is a spur gear 106. This spur gear, which is shown in dotted lines in Fig. 15, meshes with another spur gear 107 that is mounted on a countershaft (not shown) which is journaled in the frame or housing 95 parallel to the shaft 103. The axis of this countershaft is denoted at 112.

Secured to the shaft 103 to rotate with the gear 106 is a segmental gear 108, and secured to the countershaft to rotate with the gear 107 is another segmental gear 109. The two segmental gears are adapted to engage with and drive intermittently a gear 110 which is keyed to a sleeve 111 (Fig. 12).

This sleeve 111 is journaled on anti-friction bearings 113 in the housing 95 and it is keyed to one end of a shaft 114. The shaft 114 is journaled at its opposite end on an anti-friction bearing 115 which is secured in the arm 91 of the holder 90. The shaft 114 is coaxial with the arm 91 of holder 90 and its axis 117 corresponds to the axis 31 of Figs. 7 and 9.

Integral with the shaft 114 is a bevel gear 116 which meshes with the bevel pinion 87. The segmental gears 108 and 109 serve to drive the shaft 114 intermittently, first in one direction and then in the other, thereby swinging the arm 82 and the diamond 80, first in one direction and then in the other about the axis 123 of rotation of said arm 82, which axis corresponds to the axis 35' of Fig. 9. The spur gear 110 is held in its end positions by means of a ball 118. This ball is pressed by a coil spring 119 into one or the other of two suitably shaped recesses 120 which are provided on the hub of gear 110. The coil spring 119 is housed in an opening in a part of frame or housing 95. The recesses 120 are so shaped that each provides a positive stop in one direction while permitting the gear to be moved in the opposite direction toward the other stop if sufficient force is applied.

From the preceding description, it will be seen that as the paddle or piston 104 is rotated in one direction or the other through fluid pressure, the cam shaft 103 will be swung correspondingly and the cam 100 will be swung correspondingly. The swinging cam will oscillate tool holder 90 about axis 117 through operation of flat follower 101, and it will move tool holder 90 in the direction of axis 117 through operation of cam track 98 and follower 97. The swinging shaft 103 will also swing tool arm 82 intermittently first in one direction and then in the other through operation of gears 106, 107, 108, 109, 110, 116 and 87. The times, duration, and direction of swinging movement about axis 117 will depend upon the shape of the periphery of cam 100 and the direction of swing of the cam. The times, duration, and direction of movement along axis 117 will depend upon the contour of trackway 98 and the direction of swing of the cam. The times, direction and duration of swing of the tool about axis 123 will depend upon the angular positions of the segmental gears 108 and 109 about their respective axes 121 and 122.

the length of the toothed portions of the gears, and the direction of swing of shaft 103.

Thus, it will be seen that by providing a suitable control cam and suitable gearing, differing shapes of profile can be dressed on a grinding wheel. Moreover, the housing 95 may be mounted adjustably on the grinding machine with the same adjustments as disclosed in the patent of myself and Leonard O. Carlsen No. 2,311,302, issued February 16, 1943, thereby permitting further variation in the shapes that may be dressed on the side surfaces of the wheel, both convex and concave.

In Fig. 16 the cam 100 is shown as provided with a groove or trackway 98, such as would be required for dressing a grinding wheel of the type shown in Figs. 3 and 4. This groove or trackway has a portion 98' which extends in the peripheral direction, and portions 98₁ and 98₂ which are inclined to the peripheral direction. The portions 98₁ and 98₂ produce motion of the diamond holder 90 along the axis 117, while the portion 98' is a dwell portion and serves to hold the diamond in fixed axial position. As the cam 100 is turned through its angle of swing from one end to the other, the groove 98 through its engagement with the arm 97 moves the holder 90 axially, then gradually stops said axial motion, and then later causes resumption of the axial motion in the same direction as originally. This axial motion combines with the turning motion produced by the cam contour through the flat follower 101 to give the desired shape to the grinding wheel. For profiles, such as shown in Figs. 1 and 2, the central portion 98' of the groove 98 would be inclined to the periphery of the cam in the same direction but less than the end portion 98₁ and 98₂.

The cam 100 may have any desired peripheral contour. Ordinarily, a circular shape is satisfactory and is preferred because of its simplicity. The cam contour or trackway may be, for instance, a circle centered at 120 (Fig. 13), that is, at a point offset from the axis 121 of rotation of the cam shaft 103. In the turning motion of the cam 100, then, the center 120 of the peripheral contour of the cam describes a circular arc 122 about the axis 121. The end positions of movement of the center 120 in the swing of the cam are denoted at 120' and 120'', respectively. The center 120 moves between the positions 120₁ and 120₂ while the diamond is dressing the side surface 66 (Fig. 3) of the grinding wheel 65. The center moves between the positions 120'' and 120₃ while the diamond is dressing the tip portion 67 of the wheel. The center moves between positions 120₃ and 120₁ while the diamond is dressing the rounded portion 72 of the wheel profile. While the center moves between positions 120₂ and 120' adjacent point 120₂, the diamond dresses the concave chamfer surface 73 of the wheel, and while the center is moving adjacent position 120', the diamond dresses the straight shoulder portion 68 of the wheel. The diamond holder 90 has then ceased to move appreciably about its axis 117 and moves only along said axis. The same is true while the center of the wheel contour is moving between positions 120'' and 120₃. As the point of the dressing tool moves over the grinding wheel profile, the diamond point is continuously maintained at the desired constant inclination to the grinding surface by being turned intermittently about axis 123. Thus, a smooth surface is dressed on the wheel.

In the grinding wheels shown in Figs. 1 and 2, the radii of the convex and concave portions of the wheel profiles are equal. For instance, the radius of concave portion 41 of wheel 25 is the same as the radius of convex round 42. If desired, these radii can be made unequal by simply adjusting diamond pin 30 (Fig. 7) along its axis 31 without changing control cam 100. In this case, the axis 35 or 35' no longer passes through the point of the diamond. The diamond then traces a profile, such as shown in dotted lines in Fig. 1, which is equidistant from the profile shown in full lines. Similarly, the dotted line profile might be produced on the wheel 45 (Fig. 2) simply by adjustment of diamond pin 50 along axis 51 without change of the control cam.

For grinding gears or threads, wheels of contours, such as shown in Figs. 5 and 6, are used. The grinding wheel 125, shown in Fig. 5 has straight profiled sides 126 and 127 that converge to its tip 128. The tip may be flat, as shown, with rounds 129 and 130 joining it to the sides 126 and 127, respectively, or it may be fully rounded, as shown in dotted lines at 128'. Such a wheel might be of the disc, cupped, or annular type. The wheel 135, shown in Fig. 6, has a convex outer side surface 136 and a concave inner side surface 137 and is of either annular or cupped type. Its tip 138 may be flat or fully rounded.

For dressing wheels of the types shown in Figs. 5 and 6, a somewhat different form of control cam may be employed. This cam 140 (Fig. 17) may have a circular periphery, but will be swung through a greater arc 142 for dressing the two sides of a wheel than the arc 122 of swing of cam 103 in the dressing of a wheel which is to grind with one side only. The center of cam 140 is at 141 in the mean position 40 of dressing the outside surface of the wheel. The different positions of the center of the cam contour as the cam oscillates on axis 121 are denoted at 141₁, 141₂, 141', and 141'' respectively.

As the cam 140 is swung by swing of shaft 103 45 to move the center of the cam periphery from position 141₁ to position 141₂, one side of the wheel is dressed. As the cam center moves from 141₂ to 141', the tip of the wheel is dressed as a complete round like the round 128' of Fig. 5. 50 The opposite side of the wheel is dressed as the cam center moves from position 141' to position 141''.

The cam permits of dressing the outside surface of an annular grinding wheel at greater speed than the inside surface of the wheel while still dressing both sides with uniform motion of the diamond. With faster dressing, the outside surface of the wheel will be of coarser pitch than the inside surface and will be less likely to burn the work. The pressure exerted on the rotating wheel by centrifugal force tends to press the outside of the wheel against the work, and, if the outside of the wheel is dressed too fine, the outside of the wheel will burn the work. Slow uniform rotation of the diamond holder 90 about axis 117 is effected while the center of the cam is moving between positions 141' and 141'', while faster uniform rotation of the holder 90 about axis 117 is achieved during the time the center 65 of the cam is moving between positions 141₁ and 141₂.

Instead of the cam 140, which has a circular periphery and is mounted eccentrically of the shaft 103, a cam, such as shown at 150 in Fig. 75 18, may also be used. The cam 150 has two cy-

cloidal portions 151 and 152; the portion 151 lying between the points 153 and 154 of the cam periphery and the portion 152 lying between the points 157 and 158. The two portions 151 and 152 are generated conjugate to the plane contacting surface of the follower 101 and like cam 140 they effect slow uniform rotation of the diamond holder 90 about axis 117 when the cam is moving in one part of its swing and faster uniform rotation of the holder 90 about axis 117 when the cam is moving in another part of its swing. The cam periphery also contains two directly opposite circular arcuate portions 161 and 162 which are centered at 163, offset from the axis 121 of the cam shaft. The cam 150 has two other diametrically opposite circular arcuate portions 165 and 166, which are centered at 167 also offset from the axis 121 of the cam shaft. Circular arcuate portion 161 lies between the points 154 and 155 of the cam periphery. Circular arcuate portion 165 lies between the points 156 and 157 of the cam periphery. Circular arcuate portion 162 lies between the points 158 and 159 of the cam periphery. Circular arcuate portion 166 lies between the points 160 and 153 of the cam periphery. Between the circular arcuate portions 161 and 165 there is a circular arcuate portion 170 which is centered on the axis 121 of the cam shaft, and between the arcuate portions 162 and 166, there is another circular arcuate portion 171 which is also centered on the axis 121 of the cam shaft. The circular arcuate portions 161 and 165, cooperating with follower 101, serve to effect reversal of the direction of swing of the dresser tool about axis 117 while the circular arcuate portions 162 and 166 are engaging follower 97. Partial reversal is made before the tip surface of the wheel is dressed and the remainder after the tip surface is dressed. The circular arcuate portions 170 and 171 are dwell portions which are in operative position during dressing of the tip surface. They permit obtaining flat tip surfaces, such as shown in full lines at 128 and 138 in Figs. 5 and 6. The diamond holder swings about its axis 117 in the opposite direction during the dressing of the inside surface of the grinding wheel from that in which it swings during dressing of the outside surface of the wheel.

The way in which the dressing mechanism operates when a cam of the type shown in Fig. 18 is used is illustrated diagrammatically in Figs. 19 to 21 inclusive. Here 125 denotes the wheel to be dressed and 131 is the wheel axis, the wheel shown being of the annular type. In dressing the outside surface 126 of the wheel, the diamond is swung about axis 117 in the direction of the arrow 175 while being moved in the direction of this axis, as denoted by arrow 176. Both movements are at uniform velocity. In these movements, the diamond passes from position 80' to position 80'' substantially without changing its inclination. Then, as denoted by the arrow 177, the diamond holder is swung about the axis 123, so that the diamond moves from position 80'' to position 80₁, and in the continued movement of the diamond about and in the direction of axis 117, the round 129 at the juncture of the side 126 and the tip 128 of the wheel is dressed. Then the swinging movement about axis 117 ceases, but the diamond continues to move in the direction of axis 117, as denoted by arrow 176 in Fig. 20. This causes the diamond to move from position 80₁ to position 80₂ to dress the tip surface 128 of the wheel. Then, as denoted in Fig. 21,

the diamond holder is swung about the axis 123 in the same direction as before, as indicated by arrow 178 (Fig. 21) and through movement about and in the direction of axis 117, the diamond dresses the round 130 on the wheel. During the dressing of the two rounds, the direction of swing of the diamond about axis 117 may be reversed. Then the diamond dresses the inside surface 127 of the wheel by being swung about axis 117 in the direction of the arrow 179 while still moving in the direction of the arrow 176 along the axis 117. Both motions are at uniform velocity but at a relatively slow rate as compared with the dressing of outside surface 126. In these movements, the diamond passes from position 80_a to 80_b, and one dressing pass over the wheel is completed.

The two sides and the end of the wheel may, therefore, be dressed in a single swing of the control cam about axis 121. If desired, however, another dressing pass may be had during the return swing of the cam to starting position.

While the sides are being dressed, the point of the diamond is maintained at a constant or substantially constant position with reference to axis 123 but it is turned about axis 123 while the rounds at the corners of the sides and tip of the wheel are dressed. If the wheel has a flat tip and rounds are being dressed on the corners formed at the junctures at the opposite sides of the wheel and the tip, the turning motion about axis 123 may be made in two steps if desired. If the wheel is to have a fully rounded tip, as shown in dotted lines at 128' in Fig. 5, then the swing about axis 123 is made in one step. In any event, where dressing of both inside and outside surfaces of the wheel is to be effected, one of the segments 108 or 109 (Fig. 15) is omitted. The other segment is made longer than shown in that figure and, if the turning motion about axis 123 is to be effected in two steps, its teeth are arranged in two groups around its periphery with a gap between the two groups of teeth.

To dress a convex or a concave side surface on a wheel, such as is required in the case of the wheel 135 of Fig. 6, obviously all that is necessary is to properly time the motion of the tool holder 90 along axis 117 with its motion about that axis. If the curvature of the sides is considerable it may be desirable, also, to tilt the diamond about axis 123 during the dressing of the sides so as to maintain the diamond at a desirable dressing angle to the wheel surface during dressing. The motions about and in the direction of axis 117 and about axis 123 are all independent of one another, and any desired shape can be dressed on a grinding wheel simply by selection of the proper control cam and of the proper segmental gears.

While the invention has been described particularly with reference to the dressing of annular type grinding wheels, it will be understood that it is applicable to the dressing of any grinding wheel of varying profile shape, whether that wheel be a cupped, a disc, or any other type of grinding wheel. It will be understood, further, that while the invention has been described in connection with certain embodiments thereof, it is capable of various further modifications and the present application is intended to cover any variations, uses, or adaptations of the invention following, in general, the principles of the invention and including such departures from the present disclosure as come within known or customary practice in the art to which the invention pertains and as may be applied to the essential fea-

tures hereinbefore set forth and as fall within the scope of the invention or the limits of the appended claims.

Having thus described my invention, what I claim is:

1. The method of dressing side and tip surfaces of a grinding wheel which comprises swinging a dressing tool across a side surface of the wheel while moving it in the direction of its axis of swing to dress the side surface of the wheel, then swinging the tool about an axis inclined to the first axis to position the tool at substantially the same angle to the tip surface as to the side surface, and then moving the tool in the direction of the first axis to cause it to dress the tip surface of the wheel.

2. The method of dressing side and tip surfaces of a grinding wheel which comprises engaging a dressing tool with a side surface of a grinding wheel, moving the dressing tool in two directions at right angles to one another to dress the said side surface of the wheel, and then swinging the tool around the corner at the juncture at the side and tip surfaces of the wheel so that it will have substantially the same angle to the tip surface as to the side surface, and then moving the tool in one of the first named directions to dress the tip of the wheel.

3. The method of dressing side and tip surfaces of a grinding wheel, which comprises swinging a dressing tool across a side surface of the wheel while moving it in the direction of its axis of swing to dress the side surface of the wheel, then swinging the tool about an axis inclined to the first axis to position the tool at substantially the same angle to the tip surface as to the side surface, and then moving the tool in the direction of the first axis to cause it to dress the tip surface of the wheel, the first axis extending in the direction of the tip surface of the wheel.

4. The method of dressing side and tip surfaces of a grinding wheel, which comprises imparting movement to a single dressing tool in two directions at right angles to one another to dress one side surface of the wheel, then swinging the tool around the corner at the juncture of said side surface and the tip surface while continuing to impart movements in the first two directions to the tool, then moving the tool in one of the first named directions to dress the tip of the wheel, then swinging the tool in the same direction as before to turn it around the corner at the juncture of the tip surface and the opposite side surface of the wheel while moving the tool in the same direction as for tip dressing and in a direction at right angles thereto but opposite to the direction of the first named movement, and then dressing the opposite side of the wheel by continuing the last two named movements.

5. The method of dressing one side, the tip, and the opposite side surface successively of a grinding wheel which comprises engaging a dressing tool with a side of the grinding wheel, swinging the dressing tool about one axis while moving the tool in the direction of said axis to dress said side of the wheel, then swinging the tool about an axis inclined to the first named axis, then moving the tool in the direction of the first named axis further in the same direction as before to dress the tip of the wheel, then swinging the tool again about the second axis, then swinging the tool about the first axis but in a direction opposite to the direction of previous swing about that axis while continuing to move the tool

axially of said axis and in the same direction as previously to dress the opposite side of the wheel.

6. The method of dressing one side, the tip, and the opposite side surface successively of a grinding wheel, which comprises engaging a dressing tool with a side of the grinding wheel, swinging the dressing tool about one axis while moving the tool in the direction of said axis to dress said side of the wheel, then swinging the tool about an axis inclined to the first named axis, then moving the tool on further in the direction of the first named axis to dress the tip of the wheel, then swinging the tool again about the second axis, and then dressing the opposite side of the wheel by swinging the tool about the first axis but in a direction opposite to the direction of previous swing about that axis while continuing to move the tool axially of that axis and in the same axial direction as previously, the first axis being parallel to the tip surface of the wheel.

7. The method of dressing side and tip surfaces of a grinding wheel which comprises moving a dressing tool about and along an axis, and moving the tool about a second axis inclined to the first axis, the tool being moved axially of the first axis in the same direction during dressing of the side and tip surfaces, and being swung about said axis during dressing of the side surface, at least, and being swung about the second axis to maintain the tool at substantially a constant angle to the different surfaces being dressed during dressing of the same.

8. The method of dressing opposite side and tip surfaces of a grinding wheel which comprises moving a dressing tool about and along an axis, and moving the tool about a second axis inclined to the first axis, the tool being moved axially of the first axis in the same direction during dressing of the tip and both side surfaces, and being swung about said axis during dressing of the side surfaces, at least, the swinging movement being in one direction during dressing of one side of the wheel and in the opposite direction during dressing of the opposite side of the wheel, and the tool being swung about the second axis to maintain the tool at a substantially constant angle to the surfaces being dressed during dressing of the same.

9. The method of dressing surfaces on a grinding wheel which are of different inclination to the wheel axis, which comprises moving a dressing tool about and along an axis, and moving the tool about an axis inclined to the first axis, the tool being moved axially of the first axis during dressing of the different surfaces, and being moved about the first axis during dressing of one surface, at least, and being swung about the second axis to maintain the tool at a substantially constant angle to the surfaces being dressed during the dressing of the same.

10. The method of dressing the tip and opposite side surfaces of a grinding wheel with a single dressing tool which comprises moving the tool about and along an axis to dress one side of the wheel, then swinging the tool about a second axis angularly inclined to the first axis while continuing to move the tool about the first axis to dress the tip of the wheel, and

then moving the tool about and along the first axis to dress the opposite side of the wheel, the tool being swung about the first axis in opposite directions during the dressing of the opposite sides of the wheel but being moved axially of that axis in the same direction during the dressing of the two sides of the wheel.

11. The method of dressing opposite sides surfaces of a grinding wheel which comprises dressing one side surface of the wheel by swinging a dressing tool across this surface while moving the tool in one direction along its axis of swing, and dressing the opposite side surface of the wheel by swinging the tool in the opposite direction while continuing to move the tool along its axis of swing in the same direction as during the dressing of the first side of the wheel.

12. The method of dressing opposite side surfaces of a grinding wheel which comprises dressing one side surface of the wheel by swinging the dressing tool across said surface about an axis which lies in a plane perpendicular to the axis of the wheel while moving the tool along said first-named axis, and dressing the opposite side surface of the wheel by swinging the tool in the opposite direction about said first-named axis while continuing to move it along said first-named axis in the same direction as during dressing of the first side of the wheel.

13. The method of dressing opposite side surfaces of a grinding wheel which comprises dressing one side of the wheel by swinging a dressing tool in one direction about an axis which lies in a plane perpendicular to the axis of the wheel while moving the tool along the first-named axis, and dressing the opposite side surface of the wheel by swinging the tool in the opposite direction about said first-named axis while continuing to move the tool along said first-named axis in the same direction as during dressing of the first side of the wheel, the tool being swung about said first-named axis at different rates of speed during dressing of the opposite sides, respectively, of the wheel.

14. In apparatus for dressing grinding wheels, in combination, a frame, a tool holder mounted in the frame for movement about and along an axis, a tool support mounted in the tool holder for movement about an axis inclined to the axis of the tool holder, a dressing tool secured in said tool support, a rotary cam having a double trackway formed thereon, means operatively connecting the tool holder to one of the two trackways to impart rotary movement to the tool holder on rotation of the cam, means operatively connecting the tool holder to the other trackway to impart axial movement to the tool holder as the cam rotates on its axis, means operatively connected to the cam for rotating the cam, and means driven in time with the last-named means and operatively connected to the tool support for intermittently rotating the tool support on its axis.

15. In apparatus for dressing the sides and tip of a grinding wheel, in combination, a pointed rod-type dressing tool, an arm for supporting the same, means operatively connected to said arm for swinging said arm about one axis, means operatively connected to said arm

for moving said arm in the direction of said one axis, means operatively connected to said arm for swinging said arm about a second axis inclined to the first axis, the first and second means being so constructed that upon operation thereof the arm is actuated to move the dressing tool successively across one side, the tip, and the other side of the wheel, said second-named means being so constructed that the arm is moved continuously in one direction axially of the first axis during said movement of the dressing tool successively across said one side, the tip, and said other side of the wheel, said first-named means being constructed to swing the arm in one direction about the first-named axis during dressing of said one side of the wheel and to swing the arm in the opposite direction about the first-named axis during dressing of said other side of the wheel, and the third-named means being constructed to swing the arm about the second axis during operation of either of the first two means to maintain the dressing tool at the correct angle to all of the wheel surfaces during dressing of said surfaces.

16. In apparatus for dressing grinding wheels, in combination, a housing, a tool holder mounted in the housing for rotary movement about an axis and for bodily translatory movement along that axis, a tool support mounted in said holder for rotary movement independently of the holder about an axis inclined to the axis of rotation of the holder, a pointed, rod-like dressing tool mounted on the tool support, means operatively connected to the tool holder for swinging the tool holder on its axis, separate means operatively connected to the tool holder for moving the tool holder in the direction of its axis, and means operatively connected to the tool support for swinging the tool support on its axis during movement of the tool holder to maintain the dressing tool at the correct angle to the surface, which is being dressed, during movement of the tool holder.

17. In apparatus for dressing grinding wheels, in combination, a housing, a tool holder mounted in the housing for rotary movement about an axis and for bodily translatory movement along that axis, a tool support mounted in said holder for rotary movement independently of the holder about an axis inclined to and intersecting the axis of rotation of the holder, a pointed, rod-like dressing tool mounted on the tool support, means operatively connected to the tool holder for swinging the tool holder on its axis, separate means operatively connected to the tool holder for moving the tool holder in the direction of its axis, and means operatively connected to the tool support for swinging the tool support on its axis during movement of the tool holder to maintain the dressing tool at the correct angle to the surface, which is being dressed, during movement of the tool holder.

18. In apparatus for dressing grinding wheels, in combination, a housing, a tool holder mounted in the housing for rotary movement about an axis and for bodily translatory movement along that axis, a tool support mounted in said holder for rotary movement independently of the holder about an axis inclined to

the axis of rotation of the holder, a pointed, rod-like dressing tool mounted on the tool support, means operatively connected to the tool holder for swinging the tool holder intermittently about its axis, separate means operatively connected to the tool holder for moving the tool holder in the direction of its axis, and means operatively connected to the tool support for swinging the tool support on its axis during movement of the tool holder to maintain the dressing tool at the correct angle to the surface being dressed.

19. In apparatus for dressing grinding wheels, a housing, a tool holder mounted in said housing for movement therein in two directions at right angles to one another, one of said movements, at least, being rectilinear, a rotary tool arm mounted on said tool holder for movement about an axis inclined to one of the two directions of movement of the tool holder, a pointed, rod-like dressing tool secured in said arm to project radially beyond the arm, separate means operatively connected to the tool holder to move the tool holder in each of its two directions of movement, and means opera-

tively connected to said arm to move the arm about its axis during movement of the tool holder.
